3-Way Window Bird Feeder brochure, by Pat G. Kimbrough, III.

Primary Examiner—James R. Largen
Attorney, Agent, or Firm—William E. Lucas

[57] CLAIM

The ornamental design for a bird feeder, substantially as shown.

DESCRIPTION

FIG. 1 is a top plan view of a bird feeder showing my new design;

FIG. 2 is a rear elevational view thereof;

FIG. 3 is a front elevational view thereof;

FIG. 4 is a bottom plan view thereof;

FIG. 5 is an enlarged fragmentary perspective view of the left rear wall thereof;

FIG. 6 is a perspective view taken from the rear, top and right end thereof;

FIG. 7 is a left end elevational view thereof;

FIG. 8 is an enlarged fragmentary cross sectional view taken on line 8—8 of FIG. 1; and

FIG. 9 is a right end elevational view thereof.
